UNITED STATES PATENT OFFICE

WILLIAM H. VOGT, OF BIRMINGHAM, ALABAMA

COMBINATION CIGARETTE CASE

Application filed May 3, 1930. Serial No. 449,483.

This invention relates to cigarette cases and more particularly to a combination cigarette case which is adapted for use by a driver of a motor vehicle.

5 An object of this invention is to provide a combination cigarette and match case which is adapted to be mounted in any desired position on a motor vehicle and particularly on the parts of the steering wheel and the steering 10 column, the device being so constructed as to be readily fastened in any desired position.

Another object of this invention is to provide a combination article case or carrier 15 which is provided with a plurality of pockets or compartments and is so constructed that it may be readily mounted in a convenient location.

A further object of this invention is to 20 provide a combination case which is adapted to receive a package of cigarettes and when the cigarettes are mounted therein and the case closed, the cigarettes may be readily removed therefrom without entirely opening the case.

A still further object of this invention is to provide a case which may be constructed from a blank piece of flexible material and preferably leather which may be sewed or otherwise secured so as to provide a convenient carrying case.

Another object of this invention is to provide a case with a flap portion which is adapted to close the case, and at the same time the flap may be inverted so as to provide a closed loop for securing the case on a steering wheel or column or on any other bar or projection.

40 The above and various other objects and advantages of this invention will in part be described in and in part be understood from the following detailed description of the present preferred embodiment, the same being 45 illustrated in the accompanying drawings wherein:—

Figure 1 is a detail side elevation of a device constructed according to the preferred embodiment of this invention, the device being 50 shown in open or elongated position;

Figure 2 is a longitudinal sectional view taken on the line 2—2 of Figure 1;

Figure 3 is a detail side elevation of the device mounted on a supporting member;

Figure 4 is a detail side elevation of the 55 device in closed position;

Figure 5 is a detail front elevation of the device; and

Figure 6 is a sectional view taken on the 60 line 6—6 of Figure 5.

Referring to the drawings wherein like numerals of reference designate corresponding parts throughout the several views, the numeral 10 designates generally a case or container which is preferably adapted to receive a quantity of cigarettes or the like and is preferably so constructed as to receive a package of cigarettes, the cigarettes being contained in the original manufacturer's 65 wrapper.

The casing 10 is provided with a back 11, a front 12, opposite side portions 13, and a bottom 14. In actual practice, the case 10 may be constructed of a single piece of material and preferably of a material having a 70 pleasing appearance and which will not readily wear out, the material being preferably leather, imitation leather or the like.

The case 10 may be preferably stamped out of a single piece of material and the open 75 edges thereof sewed or otherwise secured together. A U shaped article receiving member 15 is secured to the outer face or front face 12 of the case 10. The U shaped member 15 is preferably open at the upper end 80 portion thereof and is adapted to receive an abrasive member 16 or the like, the member 16 being in the form of sand paper, emory cloth or the like so that matches may be struck thereupon. The article receiving 85 member 15 may be stitched, glued or otherwise secured to the front 12 of the case.

A top 17 is secured to the back 11 of the case and is preferably formed integrally therewith, the top 10 being provided with 90 slots 18 extending inwardly from the opposite ends thereof so as to provide flaps or tongues 19 so that when the top 17 is positioned against the open upper end of the case 10 the flaps or tongues 19 may be bent upwardly 95 100

so as to permit withdrawal of cigarettes or other articles from the case 10 without entirely opening the case.

A pocket member 20 is secured to the open 5 end of the top 17 and is preferably formed integrally therewith, the pocket member 20 being provided with an outer face 21 and an inner face 22, the inner face 22 having a cut out portion 23 adjacent the upper or open end 10 thereof so as to facilitate the placement or removal of articles or the like therefrom.

Preferably, the pocket 20 is adapted to receive a quantity of matches which may be either in loose form or in the conventional 15 paper package, and when the matches have been removed from the pocket 20 they may be struck upon the abrasive member 16.

A pair of reinforcing elongated straps 24 and 25 are secured to the outer face of the 20 back 11, the top 17 and the outer face 21 of the pocket member 20, the reinforcing members 24 being preferably constructed of material similar to the material of the case 10 and the pocket member 20. The reinforcing 25 members 24 and 25 may be secured to the case 10, the top 17 and the pocket 20 by means of stitching, glue, cement or the like.

A securing flap 26 is outstanding from the back 21 of the pocket member 20 and is 30 preferably formed integrally therewith, the securing flap 26 being provided with one portion 27 of a clasp which is adapted to engage the other portion 28 of the clasp which is secured to the rear 11 of the case. Preferably, the flap 20 extends across the bottom 35 14 of the case 10 and upwardly along the back 11 and in this position the articles contained within the case and the pocket 20 will not fall out.

40 In order to removably secure the combination case herein disclosed to the desired portion of a motor vehicle and preferably to the steering wheel or the steering column, the flap 26 may be unclasped from the clasp 45 28 and may be looped in such a manner as to form a closed loop, the inner face of the flap 26 engaging against the outer face of the rear member 11 and the steering column or the desired portion of the steering wheel may 50 be positioned in the closed loop formed by turning the flap 26 and the pocket member 20 rearwardly. In this position the case 10 will be maintained in opened position at all times and likewise the pocket member 20 will be 55 open so as to permit removal or withdrawal of the contents thereof.

If desired, the case 10 may be used for holding other articles besides cigarettes, such as 60 toilet articles usually contained in vanity cases or the like and the pocket member 20 may receive a small mirror or the like.

While the pocket member 20 has been disclosed as being adapted to receive a package of matches or the like, I of course do not wish 65 to be limited to this construction as the

70 pocket member may be made in such a manner as to hold larger articles than matches such as a cigarette lighter or other larger article. If desired, the flap 26 may be provided with several clasp portions 27 so that it may be conveniently secured to supporting members of various diameters or sizes and be held thereupon in substantially vertical position.

75 As disclosed in Figure 4, the case herein described is shown in closed position and it will be obvious that a convenient and small package has been provided which is adapted to receive a number of articles which may be desired by the driver of a motor vehicle or the like. In Figure 3, the case is shown in opened position, the securing flap 26 being reverted so as to provide a supporting loop for holding the case 10 on the desired support and when in this position the case 10 and the pocket 20 will, of course, be maintained in opened or operative position.

80 While the reinforcing members 24 and 25 are adapted to reinforce the case particularly where it is slotted at the top of the case 10 the members 24 and 25 are also adapted to provide a fulcrum or means by which the case 10 may be maintained in substantially vertical position at all times notwithstanding the inclination or angular position of the support upon which the device is mounted. This feature is of particular advantage where the device is mounted on a structure similar to that disclosed in Figure 3.

85 As disclosed in Figure 1 the slots 18 are 100 preferably angularly inclined from the marginal edge portions of the device converging inwardly, this being of particular advantage in the removal of articles from the case 10 without opening the device.

90 It will be obvious from the foregoing that an exceedingly practical case has been provided which may be constructed from a single piece of material which may be stamped out to form the various parts thereof, and the 95 various sections sewed or otherwise secured together so as to provide the various compartments making up the component and integral parts of the case. It will also be obvious that the case herein disclosed may also be 110 made of metal or other resilient structure which may be stamped or formed from a blank sheet of material.

115 While I have disclosed the cigarette case as being adapted to be mounted about a supporting member by reversing the flap portion 120 26 which positions the case on the supporting member in open position, I of course do not wish to be limited to this construction as, if desired, a suitable fastening member 27 may be secured to the top portion 17 so as to mount the case on a suitable supporting member in closed position but at the same time permit withdrawal or removal of the cigarettes by bending the flaps 19 upwardly.

It will, of course, be understood that various changes and modifications may be made in the details of construction and design of the above specifically described embodiment of the invention without departing from the spirit thereof, such changes and modifications being restricted only by the scope of the following claims:—

What is claimed is:—

- 10 1. A combination article case of the character described comprising a relatively large case, a **U** shaped article receiving member secured to the outer face of said case, said article receiving member being adapted to removably receive an article therein, a flexible top secured to the back of said case and integrally formed therewith, said top having relatively free flexible opposite end portions whereby to permit removal of articles from the case when the top is in closed position, an elongated pocket secured to said top and integrally formed therewith, reinforcing means secured to the rear portions of said back, top and pocket member and a securing 25 flap outstanding from said pocket member and integrally formed therewith, said securing flap being adapted to engage the bottom and rear face portion of said case whereby to close the case.
- 20 2. A combination article carrier of the character described comprising a case, securing means integrally formed with the case and adapted for engagement about a supporting article whereby to position the case on the article, said securing means comprising an elongated member integrally formed with the case, said member having an intermediate pocket, and a reversible flap.
- 25 3. A device of the character described comprising a member having an open end, a flexible closure for said open end, and coacting clasp members carried by said closure and said member for holding said closure in adjusted position, said closure when wrapped about said member overlying the open end thereof whereby to close the end, said closure being also adapted to be looped outwardly of one side of the case whereby to engage about a supporting structure.
- 30 50 In testimony whereof I hereunto affix my signature.

WILLIAM H. VOGT.
